DESIGN FOR A DISPLAY BOX

Anthony Di Domenico, Forest Hills, N. Y.

Application May 14, 1938, Serial No. 77,180

Term of patent 14 years

To all whom it may concern:

Be it known that I, Anthony Di Domenico, a citizen of the United States and resident of Forest Hills, county of Queens, and State of New York, have invented a new, original, and ornamental Design for a Display Box, of which the following is a specification, reference being had to the accompanying drawing, forming a part thereof, and in which

Figure 1 is a perspective view of a display box embodying my design;

Figure 2 is a perspective side view of the cover portion thereof; and

Figure 3 is a perspective view of the base portion thereof.

The characteristic features of my design reside in the cover portion of the display box, comprising a single piece of transparent material of the configuration shown and framed at the lower edges and corners thereof with strips of opaque material as best shown in Fig. 2 of the drawing.

I claim:

The ornamental design for a display box, as shown and described.

ANTHONY DI DOMENICO.
